(57) **CLAIM**

The ornamental design for an electric vehicle charging station, as shown and described.

DESCRIPTION

FIG. 1 is a perspective view of an electric vehicle charging station.

FIG. 2 is a front elevation view of the electric vehicle charging station of FIG. 1.

FIG. 3 is a right side elevation view of the electric vehicle charging station of FIG. 1.

FIG. 4 is a rear elevation view of the electric vehicle charging station of FIG. 1.

FIG. 5 is a left side elevation view of the electric vehicle charging station of FIG. 1.

FIG. 6 is a top plan view of the electric vehicle charging station of FIG. 1; and,

FIG. 7 is a bottom plan view of the electric vehicle charging station of FIG. 1.

The broken lines in the drawings are for the purpose of illustrating portions of the article and environmental subject matter that form no part of the claimed design.

1 Claim, 6 Drawing Sheets
